UNITED STATES PATENT OFFICE.

JOHN W. ROCKEFELLER, JR., OF NEW YORK, N. Y., ASSIGNOR TO JOHN CHATILLON & SONS, OF NEW YORK, N. Y., A CORPORATION OF NEW YORK.

DESIGN FOR A SCALE HEAD.

Application filed February 26, 1927. Serial No. 20,905. Term of patent 14 years.

To all whom it may concern:

Be it known that I, JOHN W. ROCKEFELLER, Jr., a citizen of the United States, residing at New York city, county and State of New York, have invented a certain new, original, and ornamental Design for a Scale Head, of which the following is a specification, reference being had to the accompanying drawing, forming part thereof.

Fig. 1 is a plan view of the scale head, showing my new design.

Fig. 2 is a rear elevation of the head.

Fig. 3 is a side elevation of the head.

I claim:

The ornamental design for a scale head substantially as shown.

JOHN W. ROCKEFELLER, JR.
